Primary Examiner—Doris V. Coles[57] **CLAIM**

The ornamental design for a animal repellent container, as shown and described.

DESCRIPTION

FIG. 1 is a front elevational view of the animal repellent container showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken away pole portion in FIGS. 1-4 and 7 indicates indeterminate length.
